DESIGN FOR A CALENDAR LETTER KNIFE

William B. Petzold, Pittsfield, Mass., assignor to General Electric Company, a corporation of
New York

Application March 26, 1940, Serial No. 91,251

Term of patent 14 years

To all whom it may concern:

Be it known that I, William B. Petzold, a citizen of the United States, residing at Pittsfield, in the county of Berkshire, State of Massachusetts, have invented a new, original, and ornamental Design for a Calendar Letter Knife, of which the following is a specification, reference being had to the accompanying drawing forming a part thereof.

In said drawing:

I claim:

The ornamental design for a calendar letter knife, as shown and described.

WILLIAM B. PETZOLD.
